By his Attorney, *James D. Moulton*

UNITED STATES PATENT OFFICE.

ALBERT B. DISS, OF NEWARK, NEW JERSEY, ASSIGNOR TO UNIVERSAL CASTER & FOUNDRY COMPANY, OF NEW YORK, N. Y., A CORPORATION OF NEW JERSEY.

CASTER.

Specification of Letters Patent. Patented Jan. 28, 1913.

1,051,705.

Application filed June 21, 1911. Serial No. 634,477.

To all whom it may concern:

Be it known that I, ALBERT B. DISS, a citizen of the United States, residing in the city of Newark, county of Essex, State of New Jersey, have invented certain Improvements in Casters, of which the following is a specification, accompanied by drawings.

My invention relates to casters for furniture of the type in which the caster wheel, jaws and pintle are detachable from the leg supporting plate and the parts permanently connected thereto.

The invention provides an improved and simple construction which affords means for properly supporting the furniture and permitting or facilitating its being slid about when the caster wheel, jaws and pintle are removed or withdrawn, as well as serving to coöperate with the jaws and pintle to support the furniture thereupon when the jaws and pintle are in place.

In its most complete and preferred form, the invention provides an improved structure having a leg supporting plate, a pintle holding socket secured to the plate, spring means for frictionally acting on the interior of a tubular leg to hold these parts thereto, and a leg mount member for surrounding the leg and secured to the leg supporting plate so as to substantially cover and extend beneath the edges of the plate, the leg supporting plate having a plurality of downwardly curved or bulged portions constituting slide members, upon which the furniture may easily slide when the caster wheel, jaws and pintle are not in place.

Certain other features of the invention will be understood from the following description.

The preferred embodiment of my invention is exemplified and shown in the attached drawings, in which,

Figure 1 is a perspective view showing the caster in position in relation with a furniture leg of tubular construction, Fig. 2 is a side view of Fig. 1, partly in vertical section. Fig. 3 is a bottom view with caster wheel and jaws removed. Fig. 4 is a sectional plan view of one of the details.

In the drawings A represents the caster wheel, B the jaws and C the pintle attached thereto in any appropriate manner. The pintle is retained and directed to its proper position within the leg and guided thereto

by a pintle socket composed of an inner spring member D and an outer tube E. The pintle C has at its upper extremity a head or projection F, immediately below which it is contracted to a smaller circumference. 80

Spring member D resiliently acting beneath the head F retains the pintle C within its socket, and the pintle is further maintained in such position by the action of the outer tube E directly bearing against the pintle head F. The pintle socket tube E is made to directly bear on and against the pintle by reason of the tube being at its upper extremity contracted to a smaller circumference. 70

The furniture leg G shown in square form is directly supported by the leg supporting plate H and rests thereon. The leg supporting plate H is rigidly attached to the outer tube E by any desired means, here 75 shown in the drawings by crimping the outer tube E above and below where it meets and joins the leg supporting plate H.

The pintle socket is retained within the leg by means of a resilient or spring member J which is perforated at K, and through which perforation the pintle C and the outer tube E extend, and above which perforation the tube is upset or enlarged. 80

The spring member J extends transversely around the pintle and the outer tube E, and its free ends extend downward and act frictionally outward against the interior of the leg G.

The leg supporting plate H shown as 90 square is at its corners provided with ears K which underlie portions of the leg mount L and support same. The leg mount L, which is also shown square, is inturned so as to cover and hide the edges of the leg 95 supporting plate, except where the ears K underlie the leg mount. It will be evident that these ears K are almost invisible when the leg mount is viewed from above. The inturned flange portions M of the leg mount 100 and the ears K coöperate to hold the leg mount very securely and rigidly to the leg supporting plate. The leg supporting plate is preferably dished upward by means of a circular shoulder or corrugation as seen at 105

I in Fig. 2 and indicated by the two circular lines at N in Fig. 3. This serves to stiffen the plate, as will be well understood, and also, by coming against the inner edge 110 of the foot of the leg, it may assist the leg

mount and the spring member J in centering the parts relatively to the leg. The leg supporting plate is also provided with a plurality of slide members O formed by bulging the plate downward a sufficient distance to insure the bulges or slide members projecting to a lower level than the inturned flange portions M of the leg mount, in order to allow their being used as slide supports when the wheel, jaws and pintle are withdrawn. They are made very smooth, so as to reduce friction in sliding, and they should extend down sufficiently to protect the flange portions M from contact with the floor or surface on which they rest. With the rectangular form of plate, they are preferably located at the four corners, as shown.

At P, Fig. 2, is shown a common form of ball bearings for the caster jaws, surrounding the pintle beneath the plate H.

From the foregoing description, the operation of the entire structure will be apparent. When the pintle is withdrawn, the furniture may be slid about on the slide members O, and this is particularly useful in the factory and salesroom before the furniture is sold and pintles inserted.

Without meaning to limit myself to the particular details of the form of the invention illustrated and described, I claim the following:

1. The combination of a caster socket adapted to receive a pintle, spring means carried thereby for acting frictionally on the interior of a tubular leg, a leg supporting plate secured to the said socket, a leg mount member adapted to surround the leg and having portions inturned beneath the leg supporting plate, said leg supporting plate being provided with a plurality of downwardly bulging slide members which extend below the said inturned portions.

2. The combination of a caster socket adapted to receive a pintle, spring means

carried thereby for acting frictionally on the interior of a tubular leg, a leg supporting plate secured to the said socket, a leg mount member adapted to surround the leg and having portions inturned beneath the leg supporting plate, and said plate having projections which underlie and support the leg mount member.

3. The combination of a caster socket adapted to receive a pintle, spring means carried thereby for acting frictionally on the interior of a tubular leg, a leg supporting plate secured to the said socket, a leg mount member adapted to surround the leg and carried by said plate, the said plate having a plurality of slide members bulging downward near its periphery.

4. The combination of a leg supporting plate provided with a plurality of downwardly projecting rounded slide members and a central perforation adapted to receive the caster pintle, of resilient means for securing the plate to the leg and means for detachably holding the caster pintle when in place.

5. A caster structure having a leg supporting plate which is dished or recessed upward and provided with a central perforation for receiving the caster pintle and a plurality of downwardly bulging slide members adapted to slide over a floor.

6. A caster structure having an angular leg supporting plate provided with ears and a leg mount having inturned portions which extend beneath the said plate and portions resting upon the said ears in intervals between the inturned portions.

In testimony whereof I have signed this specification in the presence of two subscribing witnesses June 17, 1911.

ALBERT B. DISS.
